UTENSIL STERILIZER AND DRYER COMBINATION

Mozel A. Adams, Rayne, La., assignor to Trex Corporation, Eunice, La., a corporation of Louisiana

Filed Mar. 24, 1958, Ser. No. 50,153

Term of patent 3½ years

(Cl. D83—1)

Fig. 2

Fig. 1 is a top perspective view taken from the front and right end of a utensil sterilizer and dryer combination, showing my new design, the bottom and rear appearing as plain rectangles and the left end appearing as a plain substantial square of the same dimensions as the right end shown; and

Fig. 2 is a vertical cross-sectional view thereof taken on line 2—2 of Fig. 1.

I claim:

The ornamental design for a utensil sterilizer and dryer combination, as shown and described.
